(57) **CLAIM**

We claim the ornamental design for an electric dirt bike, as shown and described.

DESCRIPTION

FIG. 1 is a perspective view of an electric dirt bike embodying the invention.

FIG. 2 is a left side elevation view of an electric dirt bike shown in FIG. 1.

FIG. 3 is a right side elevation view of an electric dirt bike shown in FIG. 1.

FIG. 4 is a front elevation view of an electric dirt bike shown in FIG. 1.

FIG. 5 is a rear elevation view of an electric dirt bike shown in FIG. 1.

FIG. 6 is a top plan view of an electric dirt bike shown in FIG. 1; and,

FIG. 7 is a bottom plan view of an electric dirt bike shown in FIG. 1.

The broken lines shown in the drawings illustrate portions of the electric dirt bike that form no part of the claimed design.
